UNITED STATES PATENT OFFICE.

SIDNEY A. KELLER, OF NEW YORK, N. Y., ASSIGNOR TO EASTWOOD-PARK COMPANY, OF NEWARK, NEW JERSEY, A CORPORATION OF NEW JERSEY.

DESIGN FOR A HAND-MIRROR OR SIMILAR ARTICLE.

No. 39,656.

Specification for Design.

Patented Nov. 3, 1908.

Application filed April 10, 1908. Serial No. 426,397. Term of patent 3½ years.

To all whom it may concern:

Be it known that I, SIDNEY A. KELLER, a citizen of the United States, and resident of the city, county, and State of New York, have invented a new, original, and ornamental Design for Hand-Mirrors or Similar Articles, of which the following is a specification, reference being had to the accompanying drawing, forming part thereof.

Figures 1 and 2 are back and front views, respectively, of a hand mirror, or similar article, showing my new design.

The salient features of the design reside in the peculiar contour of the back and handle; in the surface design thereon; and in the peculiar contour of the mirror.

I claim:

The ornamental design for a hand mirror or similar article, as shown and described.

SIDNEY A. KELLER.
